United States Patent Office

Des. 186,413
Patented Oct. 20, 1959

186,413

BOTTLE

Robert P. Vuillemenot, Oradell, N.J., assignor to The Procter & Gamble Company, Cincinnati, Ohio, a corporation of Ohio

Application June 26, 1959, Serial No. 56,554

Term of patent 14 years

(Cl. D58—8)

FIG.4.

FIG.1.

FIG.3.

FIG.2.

The rear elevation and the side elevation, not shown, are the same as the front elevation and side elevation shown.

I claim:

The ornamental design for a bottle, as shown and described.
